UNITED STATES PATENT OFFICE.

ALBERT VETTER, OF TOLEDO, OHIO, ASSIGNOR TO THE WILLYS-OVERLAND COMPANY, OF TOLEDO, OHIO, A CORPORATION OF OHIO.

BEAD STRIP.

Application filed March 21, 1919. Serial No. 284,142.

To all whom it may concern:

Be it known that I, ALBERT VETTER, a citizen of the United States, residing at Toledo, in the county of Lucas and State of Ohio, **5** have invented certain new and useful Improvements in Bead Strips, of which I declare the following to be a full, clear, and exact description.

This invention relates to improvements in **10** bead strips and securing means therefor, and while it is illustrated herewith in connection with the application of an ornamental beading to portions of an automobile top, the invention is not limited to the application of **15** a beading to a vehicle top, but may be employed wherever it is found desirable to use a beading of this character.

One object of the invention is to provide **20** an improved form of beading, which may be readily and economically manufactured, and easily applied wherever its use is found to be desirable.

A further object of the invention is to provide improved means for securing a beading **25** of this character to a frame.

A further object of the invention is to provide improved interlocking means for securing **30** two members together.

A further object of the invention is to provide **35** means for securing an ornamental bead to a frame member in such a manner that the securing means will be housed within and concealed by the ornamental bead.

A further object of the invention is to provide **40** an improved form of clip which may be employed for retaining two members in proper position relative to each other.

Further objects of the invention relate to **45** economies of manufacture and details of construction, as will hereinafter appear from the detailed description to follow.

The objects of the invention are accomplished in one instance by the devices and means described in the following specification, **50** but it is evident that the same may be varied widely without departing from the scope of the invention as pointed out in the appended claims.

A structure constituting one embodiment **55** of the invention, which may be the preferred, is illustrated in the accompanying drawing forming a part hereof, in which:

Figure I is a perspective view of an automobile body illustrating the improved beading as applied to the bows of the top.

Figure II is a sectional view through the rear bow, taken along the line II—II of Figure I, and illustrating the manner of securing the bead strip to the bow.

Figure III is a perspective view of a section of the bead strip.

Figure IV is a perspective view of one of the clips employed for securing the bead strip to a frame.

In the application of ornamental beading **60** to vehicle frames, such as automobile tops and the like, it has been customary to employ rounded or semi-cylindrical strips of beading formed of aluminum or some similar metal, and having embedded in the under **65** surface thereof at suitable intervals throughout the strips a plurality of nails which are adapted to be driven into the frame member for the purpose of properly retaining the ornamental bead in position upon the frame. **70** This form of bead and the manner of applying the same has been found to be objectionable by reason of the fact that when the **75** frame member is formed of hard wood, as is the case in the construction of bows employed in connection with automobile tops, some of the nails are apt to become bent or broken as they are driven into the wood, or some of the heads of the nails forced through the outer surface of the bead strip. The **80** form of bead strip illustrated herewith and the method of applying the same to a frame member eliminates these objectionable features of bead construction, and also provides

a form of bead strip which can be manufactured **85** more cheaply, and applied more easily than that ordinarily employed. It will also be understood that the improved bead construction and manner of securing the same to a frame is quite as applicable to an all **90** metal bow, in which connection the usual construction of bead strip could not be used, as the nails or staples secured to the strip and ordinarily employed to secure the same to a bow could not be used since the nails **95** or staples could not be forced into the all metal bow.

In the drawings, similar reference characters refer to corresponding parts throughout the several views, and the sectional view **100** is taken looking in the direction of the small arrows at the ends of the section line.

In the embodiment of the invention illustrated herewith, 10 designates an automobile body of the usual construction, pro- **105**

vided with a front bow 11 and a rear bow 12, to which are applied strips 13 of the ornamental beading described herewith.

The rear bow 12 as illustrated in Figure II, is covered with a strip of fabric 14 such as is ordinarily employed for the purpose of covering the bows of automobile tops, and has secured thereto, a rear apron portion 16, which is adapted to be secured at its lower end to the rear frame portion of the automobile in the usual manner. The fabric 17 forming the cover portion of the top is adapted to be passed over the rear bow and secured thereto by the means employed for securing the ornamental beading thereto. The usual finish beading 18 is provided with a narrow strip of fabric covering 19, the ends of which are adapted to lie against the rear surface of the bow and be secured thereto in any desired manner, as by the securing means employed for attaching the beading to the bow.

Positioned at suitable intervals along the exterior surface of the rear bow, and in line with each other are a plurality of clips 20, each of which is adapted to be secured in position and retained upon the bow by means of a nail or other suitable fastening means 21. Each of these clips is provided with a base portion 22 provided with an opening 23 formed therein for the reception of one of the nails 21, and each of these clips has a pair of side walls 24 extending at substantially right angles to the base portion 23, and so arranged as to be substantially parallel to each other and form with the base portion a channel-shaped member. The upper part of the side walls 24 is provided with an outwardly extending downwardly inclined flange 25, the outer edges of which are substantially parallel to each other, and which are preferably formed of resilient material. The bead strip 13 is of rounded or semi-cylindrical construction, and is provided with a pair of inturned flanges 27 positioned upon the opposite side edges thereof, and extending inwardly toward the inner or central portion of the bead. After the clips or catches 20 have been properly positioned upon the frame member and secured thereto in such a manner that the corresponding side edges of the several catches are in substantial alignment, the bead strip 13 is placed thereover and pressed into close engagement therewith in such a manner that the inturned flanges 27 upon the bead member will snap over the out-turned downwardly inclined flanges positioned upon opposite sides of the clips in such a manner as to engage beneath the under surfaces of these flanges, as illustrated in Figure II, and thus securely interlock the cooperating mating edges of the bead strip and clip, in such a manner as to securely re-

tain the bead strip in position upon the frame member.

It will be understood that the cover strip 14, the cover portion 17 of the top, and the finish beading 18, together with the strip of fabric 19 carried thereby, are preferably all properly positioned upon the bow and secured in place thereon by means of the nails or other suitable fastening means employed for securing the ornamental beading to the bow. However, if it is found to be desirable, separate securing means may be employed for attaching these parts to the bow in such a manner as to properly hold them in position relatively to the bow while the clips 20 are being applied thereto. After the application of the clips 20, the nails or other fastening means employed for securing the clips to the bows will supplement the means used for attaching the various fabric elements thereto and assist in firmly securing these parts in position.

It will be understood that the ornamental beading shown herewith may be secured to an all metal bow quite as readily and in a manner similar to that employed in attaching the same to the wood bow as shown and described herewith. In the application of the ornamental beading to an all metal bow, machine screws are preferably substituted for the nails 21, and the fabric portions 14, 17 and 19 may or may not be separately attached to the bow prior to the application of the clips thereto. It will be understood that the clips 20 to be used in connection with all metal bows are identical in all respects to those employed with the wooden bows and are positioned upon the bow in the same manner to permit a ready application of the ornamental beading thereto.

The bead strip 13 and the inturned flanges 27 formed integral therewith, are preferably made of resilient material, so that upon pressure being exerted upon the bead strip, the in-turned flanges will slide over and engage beneath the out-turned flanges of the several clips. The clips 20 may or may not be formed of resilient material in such a manner that the out-turned flanged portions thereof will be bent inwardly under the pressure exerted upon the bead strip and then returned to their original positions after passing the edges of the in-turned flanges 27. It will be seen that the edges of the out-turned downwardly inclined flanges 25 are substantially parallel with each other, and also to the edges of the in-turned flanges 27 formed upon the bead strip, thus insuring the proper engagement of the in-turned flanges 27 by the out-turned flanges 25 of each clip member. While it is believed to be preferable to form the bead strip of more resilient material than the various clip mem-

bers so that the in-turned flanges 27 will be thrust apart as the bead strip is forced against the clip members, thereby sliding over the out-turned flanges 25 and engaging 5 behind the same for the purpose of locking the members together, it is apparent that the bead strip may be made of rigid material and the clips formed of sufficiently thin resilient material so that the out-turned flanges 10 25 thereof will be forced towards each other as the bead strip is pressed there-against, and thus slide over and engage behind the in-turned flanges 27. It will be understood, therefore, that either or both of these members 15 may be formed of resilient material, thus permitting either or both sets of co-operating flanges to be thrust out of their original position for engagement behind the co-operating flanges carried by the other 20 members for the purpose of securing the two members together.

While I have shown and described in considerable detail a specific embodiment of my invention, it is to be understood that this 25 showing and description is illustrative only, and for the purpose of rendering my invention more clear, and that I do not regard the invention as limited to the details of construction illustrated or described, nor any of 30 them, except insofar as I have included such limitation within the terms of the following claims, in which it is my intention to claim all novelty inherent in my invention broadly as well as specifically.

35 What I claim as new and desire to secure by Letters Patent is:

1. In a vehicle structure, a frame member, a plurality of clips fixed thereto and having inclined faces formed at opposite sides 40 thereof, and a bead strip adapted when pressed against said inclined faces to engage over the same and thereby be secured to said frame.

2. In a vehicle structure, a frame member, 5 fabric overlying said frame member, a bead strip having inturned edge portions and means comprising clips for securing said fabric to said frame, said clips having inclined edge portions whereby when said bead 50 strip is pressed against said clips its in-turned edges ride over said edge portions.

3. In a vehicle structure, a frame member, fabric overlying said frame member, a sheet metal bead strip, having inwardly projecting edge portions, and a plurality of sheet 55 metal clips each having a backwardly inclined edge portion whereby when said bead strip is applied directly to said clips it is caused to spread and to automatically inter-lock with said clips. 60

4. In a vehicle structure, a frame member, a fabric cover therefor, means comprising a clip for binding said cover to said frame member, said clip having a flat central portion and backwardly inclined edge portions, 65 and a transversely curved bead having in-turned edges adapted to slide over said inclined edge portions and become locked against disengagement therefrom.

5. In a vehicle structure, a frame member, 70 a fabric cover therefor, means comprising a series of clips for securing said cover to said frame member, each of said clips having a central fabric engaging portion bordered by upstanding portions the outer edge portions 75 of which slope rearwardly, and a rounded resilient bead having inturned edges said bead being adapted to spread when pressed against the sloping portions of said clips and become hooked thereover. 80

6. In combination, a bead strip made of resilient sheet metal and having inturned side edges, a plurality of clips each of which is adapted to be secured to a support and is provided with downwardly and outwardly 85 inclined edges spaced from the support, whereby said bead strip may be pressed upon said clips to the end that its side edges shall ride over the inclined side edges of the clips and engage therebeneath. 90

7. In combination, a bead strip having in-turned side edges, a plurality of resilient metal clips, each of which is adapted to be secured to a support and is provided with downwardly and outwardly inclined edges 95 spaced from the support, whereby said bead strip may be pressed upon said clips to the end that its side edges shall ride over the inclined side edges of the clips and engage therebeneath. 100

In testimony whereof, I affix my signature.

ALBERT VETTER.
